United States Patent Office

Des. 212,900
Patented Dec. 10, 1968

212,900

OUTDOOR LIGHTING FIXTURE

Donald V. Vesely, Hillside, and David R. Dalpiaz, Elmhurst, Ill., assignors to Guardian Light Company, Oak Park, Ill., a corporation of Illinois

Original design application Oct. 12, 1967, Ser. No. 8,967.
Divided and this application May 3, 1968, Ser. No.
11,777

Term of patent 14 years

(Cl. D48—31)

FIG.1

FIG.2

FIG.3

FIG.4

FIG.5

FIG. 1 is a perspective view of a lighting fixture embodying our new design;

FIG. 2 is a bottom plan view of the fixture shown in FIG. 1;

FIG. 3 is a rear elevation of the fixture shown in FIG. 1;

FIG. 4 is a side elevation of the fixture shown in FIG. 1; and

FIG. 5 is a top plan view of the fixture shown in FIG. 1. This is a division of design application Ser. No. 8,967, filed Oct. 12, 1967, and now abandoned.

We claim:

The ornamental design for an outdoor lighting fixture, substantially as shown.
